UNITED STATES PATENT OFFICE

ROBERT GUILLEMOT, OF ST. MAUR DES FOSSES, FRANCE, ASSIGNOR TO SCOTT & WILLIAMS, INCORPORATED, OF NEW YORK, N. Y., A CORPORATION OF MASSACHUSETTS

METHOD AND APPARATUS FOR FORMING KNITTED LOOPS IN HOSIERY MACHINES

Application filed October 1, 1926, Serial No. 138,892, and in France October 1, 1925.

This invention relates to a new method of forming loops for all hosiery machines in which stitches are made by means of movable latch needles, spring needles etc., as for example: flat knitting machines, circular knitting machines, underwear knitting machines, and the like.

This new method of forming loops, while securing a regular knocking over, allows of making on such machines of given gauge a tighter and finer stitch than that which can be made by using the same yarn numbers on a machine of the very same gauge and type fitted with the old method of forming the loops.

15 The method of obtaining a tight stitch by means of this new method of forming loops has no relation to the method of obtaining a tight stitch by the known system of determining the position of the stitch cams with respect to the needles or the position of the cylinder needles with respect to the stitch cams.

25 Specially applied to automatic seamless knitting machines for making hose or half-hose, this new method of forming loops on a machine of given gauge allows, by slackening the stitch, the making of hose with a very wide welt, and also, by tightening the stitch, the making of a much narrower ankle and 30 foot than those which can be made on the same machine fitted with the known method of forming loops, and this without any cuts or defects in the fabric.

35 This new method of forming loops is hereafter described as applied on a seamless circular machine of the Scott & Williams type for making hose or half-hose, this machine working with latch needles. This new method can likewise be applied on the same conditions on similar types of seamless machines or other types working with latch needles or 40 spring needles, etc.

45 Fig. 1 is an extended elevation of the yarn, needles and sinkers at the knitting point showing the new method being carried out;

Fig. 2 is an enlarged view of a piece of fabric showing diagrammatically how the loops are equalized;

50 Figs. 3 and 4 are side elevations of the new high and low ledge sinkers respectively;

Figs. 5 and 6 are side elevations of modified forms of the new high and low ledge sinkers respectively;

Fig. 7 is a side elevation of a low ledge sinker showing a needle tipped radially to 55 equalize the loops.

On machines of a given gauge knitting with yarns of suitable thickness, the tightness and fineness of the stitch are mostly determined by the length of the yarn drawn by 60 the needles, that is to say, determined by the distance between the knocking over edge or ledge of the sinkers (which ledge in the known method of forming loops is on all sinkers at the same height above the needle cylinder), and the hook of the needle when the needle for the knocking over has been put on its lower position.

If, for obtaining a tighter stitch by the old procedure of forming loops, the distance between the ledge of the sinker and the hook of the needle in its lower or knocking over position is reduced beyond a certain limit, the loop previously made knocks over with difficulty and the needles load up, making defects 70 or cuts in the fabric.

For reducing the length of the yarn drawn by the needles and obtaining a tighter and finer stitch, and at the same time securing a regular knocking over, there are used, in 80 this new method, two kinds of sinkers: a sinker *e* or *e'* with a high ledge *i* or *i'* (Fig. 3 or 5) and a sinker *h* or *h'* with a low ledge *i*¹ or *i*⁵ (Fig. 4 or 6) these two kinds of sinkers sliding as usual in the inside 85 and outside sinker rings. In any one machine sinkers *e* and *h* are used together or *e'* and *h'* are so used as an alternative. These two sets *e*, *h* and *e'*, *h'*, are different embodiments of the invention. A set consists, in 90 either case, of a sinker having a high ledge and one having a low ledge and two such sinkers are used side by side. A number of such sets are used in a machine, the high and low ledge sinkers being alternated, as shown in Fig. 1, where *e* and *h* represent respectively sinkers having high and low knocking-over ledges. Fig. 1 is intended to show the invention generically without limitation to either the *e*, *h* or the *e'*, *h'* type of sinker.

It is found that by forming adjacent needle wales or loops alternately larger and smaller than the desired final loop and then equalizing these alternate loops, the resultant loop formed, which is the mean of the large and small ones initially formed, is smaller than previously has been possible when all loops were drawn of equal size. What has been referred to here as the large loop is best defined as being at least as large as can be knocked over when all loops are of the same size. The small loop formed by the needle adjacent to that forming the so-called large loop, is considerably smaller than any heretofore made under the same conditions, and is smaller than the smallest equalized loop possible with this method. It is the cooperation between adjacent large and small loop forming mechanisms and the equalization of the resulting large and small loops that gives a final loop smaller than heretofore known. In the embodiment shown, the lower edge v of the upper arm of the sinker is at the same distance above the sinker ring level, or other common level, in sinkers of either type, e , h or e' , h' . But the dimension a between the lower edge v and the ledge i of the upper arm s of the sinker e (Fig. 3) is greater than the dimension c of the corresponding portion of the upper arm t of sinker h (Fig. 4). So also with dimension a' and c' on the modified sinkers e' and h' of Figs. 5 and 6 respectively.

Viewing Figs. 3 and 4, it is seen that a needle b in coming into its lower or knocking-over position draws a greater length of thread over the ledge i of arm s of a sinker e than does a needle b associated with the arm t on the adjacent sinker h . Referring to Figs. 5 and 6, the same is true, i. e., that the length of thread drawn over ledge i' of arm s' is greater than that drawn over ledge i' of arm t' .

The result of this on a series of sinkers of alternate high and low ledge is shown in Figure 1.

For example, taking a series of needles numbered from 1 to 12 (Fig. 1), the length of yarn drawn by the needles 6 and 7 partly on the sinker e (with high ledge), and partly on the sinker h (with low ledge) is of course shorter than the length of yarn which could be drawn by the same needles if the sinker h with low ledge were replaced by a sinker e with high ledge, as indicated by a dotted line, Fig. 1.

The loop previously drawn leans on the one side on the high ledge of the high sinker e , and on the other side on the ledge of the low sinker h , the sides of the loop having different inclinations as shown. It happens, as shown in Fig. 1, that the long side of this loop leaning on the sinker e easily slides over the hook of the needle and that the short side of this loop leaning on the low sinker h

is drawn along and forced to slide likewise over the hook of the same needle, thus securing a regular knocking over.

The length of the yarn drawn on the ledge of sinker h being shorter than the length of the yarn drawn on the higher ledge of the sinker e , consequently the stitch formed on the sinker h is shorter than the stitch formed on sinker e and an uneven fabric results, composed of alternate long stitches m and short stitches n , Fig. 2. These long and short loops may be equalized in different ways, all depending upon the same underlying idea. Since the length of a loop is determined by the distance between the point of engagement of the thread with the knocking-over ledge and the point where the needle engages the thread at the knocking-over, it follows that by changing this spacing after knocking-over, the length of loop may be changed. After the knocking-over, to effect equalization of the unequal loops initially drawn, any relative movement of the needle and sinker may be availed of provided it brings the thread to such a position on the sinker that the point of engagement of the thread and sinker and the point of engagement of needle and thread have a new spaced relation which is the same for all sinkers. The thread will accommodate itself to this new spacing, the long loops being robbed and the short ones lengthened until all loops are of equal length.

One way of equalizing loops is to use a sinker e with a high ledge i and a slope o Fig. 3, and a sinker h with a low ledge i' and a slope p , Fig. 4, both sinkers e and h having a throat of the same height above the cylinder, that is, with dimension w equal to dimension w . The needles having knocked over the stitches, the sinkers e and h are pushed forward and the needles rise. By this movement, the shorter loops formed on sinker h are obliged to ascend the slope p Fig. 4, whilst the longer loops formed on the sinkers e are obliged to descend the slope o , Fig. 3. In doing this, the yarn g will shift lengthwise until it accommodates itself on the throats. The depths of the throats being the same, the loops, when on them, will be of the same size.

Another way is to use a sinker e' with a high ledge and a deep throat y under its nose, Fig. 5, and a sinker h' with a low ledge and a less deep throat y' under its nose, as in Fig. 6. The depth of the throat is the dimension in the direction of the arrow. After knocking over, the needles are rising to a certain height and the sinkers are moving forward so that the inner end of the throat y' engages the thread on sinker h' before the inner end of throat y engages the thread on e' . This causes the thread to shift lengthwise, robbing the long loop on e' until an equal length lies between each sinker and needle. The yarn

then is slack on the shallow throat in the sinker in Fig. 5.

This result can also be obtained by moving the hook ends of the needle radially outward by any well known means. Such a movement is shown in Fig. 7.

According to the nature, elasticity and thickness of the yarns used, and to the slackness or tightness of the fabric, the difference 10 of height between the sinkers with high and low ledges can be made greater or less, likewise the difference in the depths of the throats of the sinkers e^1 and h^1 , or the pushing away of the needles from the center of the cylinder can be made greater, more or less, so that in these latter cases, the differences of the strain exercised by each of these sinkers or needles on their stitches may be stronger more or less.

20 What I claim is:

1. A method of forming loops of yarn in knitting machines, adapted to produce a tighter and finer stitch whilst simultaneously securing a regular knocking over of same, 25 the method comprising the steps of forming the loops over edges of different height some of which edges are not high enough by themselves to knock over the stitch so as to form longer stitches upon some edges than upon 30 others, and subsequently equalizing the long and short stitches thus produced.

2. The method of forming stitches which consists in forming, at the knocking-over operation, adjacent loops of unequal size, the 35 smaller loop being smaller than, and the larger loop being at least as large as, the smallest loop that can be knocked over when adjacent loops are formed of equal size.

3. The method of forming stitches which 40 consists in forming, at the knocking-over operation, adjacent loops of unequal size, the smaller loop being smaller than, and the larger loop being at least as large as, the smallest loop that can be knocked over when 45 adjacent loops are formed of equal size, and then equalizing these loops after the knocking-over operation.

4. The method of forming stitches which 50 consists in producing, at the knocking-over operation, at adjacent stitch forming mechanisms, different space relations between the point of engagement of needle and thread and the point of engagement of the thread and the knocking-over ledge, and then causing 55 subsequent relative movement between sinker and needle and utilizing the subsequent relative movement to cause the thread to shift to new positions on the sinkers such that the said space relations are the same 60 at adjacent stitch forming mechanisms.

5. In a knitting machine having sinkers and needles with means for producing varying relative positions therebetween during the stitch forming operation, and means for 65 guiding a thread into association therewith;

that construction of the sinkers in which the portions, on adjacent sinkers, for engaging the thread at knocking-over, are spaced different extents from the position occupied by the portion of the needle engaging the 70 thread at knocking-over, and the portions of adjacent sinkers for engaging the thread after knocking-over are spaced a uniform distance from the position occupied by the portion of the needle engaging the thread 75 after knocking-over.

6. A web-holding sinker for a knitting machine having a loop-forming ledge at a higher level than the bottom of the throat, in combination with a cooperating sinker having a loop forming ledge at a lower level than the bottom of the throat, the ledges of the two sinkers being at different heights and the throats being of the same height and depth.

In testimony whereof I have signed my name to this specification.
